UNITED STATES PATENT OFFICE.

GEORGE S. TIFFANY, OF HIGHLAND PARK, ILLINOIS, ASSIGNOR TO THE GRAY NATIONAL TELAUTOGRAPH COMPANY, OF RICHMOND, VIRGINIA.

TELAUTOGRAPH.

SPECIFICATION forming part of Letters Patent No. 617,891, dated January 17, 1899.

Application filed February 8, 1897. Renewed July 29, 1898. Serial No. 687,232. (No model.)

To all whom it may concern:

Be it known that I, GEORGE S. TIFFANY, a citizen of the United States, residing at Highland Park, county of Lake, and State of Illinois, have invented certain new and useful Improvements in Telautographs, fully described and represented in the following specification and the accompanying drawings, forming a part of the same.

10 My invention consists in improvements upon telautographic instruments heretofore patented by me.

In my present instrument I propose to dispense with the mechanism commonly employed outside of the escapement-magnet itself for propelling the receiving-pen and to cause the receiving-pen to be moved by the action of the escapement-magnet, and I have devised an organization of circuits whereby 20 the quickness of action of the escapement-magnet is increased. This arrangement of circuits is particularly useful where the escapement is propelled by the escapement-magnets, but is of advantage in other constructions in order to quicken the action of the escapement.

Stated in general terms, it consists in providing a circuit-breaker on the armature of the escapement-magnet which shall act to 30 modify the circuits which control the escapement-magnet after each movement of the armature, so that the ensuing movement of the armature may be expedited.

My invention also consists in improvements for bringing the receiving instrument into unison with the transmitting instrument by causing the receiving-pen to move in a given direction under the impulse of currents actuating the escapement-magnets until such 40 currents are interrupted at the point where the instrument reaches the unison position.

In the drawings forming a part of this specification, Figure 1 is a plan view, and Fig. 2 a side elevation, of the escapement and reversing magnets. Fig. 3 is a cross-section on the line 3 of Figs. 1 and 2. Fig. 4 is a diagram of the circuit connections. Fig. 5 shows a modification.

I will first describe the escapement and reversing mechanism, referring particularly to Figs. 1, 2, and 3. The escapement-magnet E is

provided with a centrally-pivoted vibrating armature 1, which carries insulated contact-springs 2 3, each adapted when the corresponding end of the armature 1 is released to come 55 into contact with one of two contacts 4 5. Fixed to the armature is a forked projection 6, carrying spring-pawls 7 8, adapted to engage with the ratchet-wheel 9 and propel the same. The pawls are respectively provided with 60 stops 10, carried by the arm 6, and 11, fixed on the frame, which act to lock the pawls in the position in which they are thrown and prevent any further movement of the ratchet-wheel under the inertia of the pen-arm. The 65 ratchet-wheel 9 is loosely mounted upon a shaft 12 and connected thereto by a spring 13, the purpose of this spring connection being to prevent abrupt jars from being transmitted from the escapement to the receiving-pen. Freely journaled on the shaft are two 70 miter gear-wheels 14 and 15, connected by a third wheel 16, journaled in the frame. Between the gear-wheels 14 and 15 are two friction-disks 17 and 18, mounted upon a sleeve 75 19, which is keyed to the shaft. Attached to the upper gear-wheel 15 is a pen-drum 20, also freely revolving on shaft 12. These disks and wheels constitute together a reversing-clutch. The vertical position of the disks 17 80 and 18 is determined by a lever 21, to one end of which is attached the armature 22 of reversing-magnet H, the pull of the magnet on this armature being opposed by spring 23. Attached to the frame is the contact-spring 85 24 and contact 25, the use of which will be hereinafter mentioned.

Referring now to Fig. 4, the circuits will be explained. The interrupter is shown in diagram in the right-hand portion of the figure and is one of the usual forms of construction, the movement of the pen-arm in one direction sending impulses successively of one polarity to line and the movement of the pen-arm in the other direction sending impulses 95 successively of the opposite polarity to line. These pulsations arrive at the receiving instrument over the line-wire L and at 26 divide, part passing through the non-inductive resistance R and part passing through polar 100 relay F to binding-post 27 and to magnet D, which controls the escapement. From bind-

ing-post 27 the circuit passes through coil d of magnet D to binding-post 28 and ground. The other branch of the circuit from dividing-point 26 is through the resistance R, binding-post 29, coil d' of magnet D, binding-post 28, and ground. The non-inductive resistance and the magnet-coils of F are made of about the same resistance; but owing to the self-induction of the magnet-coils most of the current will at first pass through the branch in which the resistance is located, energizing the coil d' more than the coil d and attracting the pivoted armature 30 toward the coil d' and causing its other end to recede from the coil d . In this position it is in contact with the stop 31, and in its opposite position it is in contact with stop 32. When the line-current is interrupted, the coils of relay F give forth an induced current, which passes through the coil d in the same direction as the line-current and through the coil d' in the opposite direction to the line-current, reversing the position of the armature 30 and causing it to return to the position shown in Fig. 4. In the latter position of the armature 30 a circuit will be closed from battery Z through switch S, wire a , heel-piece 33 of magnet D, armature 30, contact 32, wire a' , coil e of magnet E, wire a^2 to battery, drawing the armature 1 into the position shown in Fig. 4. In this position a circuit will be closed from battery Z through wire a^2 , coil e' of magnet E, wire b , contact 5, spring 3, wire b' , contact-stop 25, spring 24, wire b^2 to battery. This circuit, however, being formed subsequently to the closing of the circuit through coil e , does not disturb the position of the armature 1. When the armature 30 moves so as to fall against the contact-stop 31, the circuit previously passing through the coil e is broken and the armature 1 turns on its pivot under the pull of the coil e' . This movement of the armature breaks the circuit of the coil e' which passed through the spring 3 and contact 5; but at the same time another circuit for that coil is closed from battery Z through switch S, wire a , armature 30, stop 31, wire f , wire b , coil e' , and wire b^2 , which continues to hold the armature attracted toward the coil e' . When the spring 2 strikes the contact 4, a circuit is closed from battery Z through wire a^2 , coil e , wire a' , stop 4, spring 2, wire b' , contact 25, spring 24, and wire b^2 to battery. As the armature is now held attracted by the coil e' , its position is not affected, however, by the closing of this circuit through the coil e . The successive changes of position of the armature 1 cause the pawls 7 8 to drive the ratchet-wheel 9 forward. It will be observed that on each movement of the armature 30 the armature 1 is caused to move under the pull of an already-closed circuit. Its movement is therefore effected by the breaking of the circuit and demagnetization of the coil instead of by the closing of the circuit and the magnetization of the coil, as is usual. As demagnetization

occupies less time than magnetization, an increased promptness of movement in the armature 1 is effected. This is of especial importance where the escapement is operated by the armature so moved; but it is also capable of advantageous use in an instrument where in the escapement merely controls the application of a continuous power or tension to the receiving-pen.

The reversal of movement is effected as follows: With one polarity of the line-current the armature 33 will be in the position shown in Fig. 4, and when the polarity of the line-current is reversed, following the reversal in movement of the transmitting-pen, its position will be against the stop 34. In the latter position a circuit is closed from battery Z through switch S, wires a g , armature 33, stop 34, wire g' , magnet H, and wire g^2 to battery, causing the magnet H to attract its armature and raise disk 17 into contact with gear 15, reversing the direction of movement of the receiving-pen. When, therefore, the armature 33 is in the position shown in Fig. 4, the position of the disks 17 and 18 will be controlled by the spring 23 and the receiving-pen will move in a corresponding direction, and when armature 33 is against the stop 34 the position of the disks 17 and 18 will be controlled by the magnet H and the movement of the receiving-pen will be reversed.

In order to provide for bringing the receiving instrument into unison with the transmitting instrument, I attach a collar 35 to the pen-arm 36 in such a position as to come in contact with the spring 24 and move it away from the contact 25. On each shifting of the paper the switch S is opened by the paper-shifting mechanism at the receiver. The controlling-circuits of the escapement-magnets are therefore interrupted, and the escapement-magnets are free to move under the influence of the local circuits, before described, passing through the springs 2 3 and contacts 4 5. These circuits will cause the armature 1 to vibrate, and consequently the ratchet-wheel 9 to revolve, moving the pen-arm 36.

The organization of circuits is such that while the paper is being shifted the armature 33 is in the position shown in Fig. 4, so that the disk 18 is in contact with the gear-wheel 14, which will cause the pen-arm to move toward the left, as shown in Fig. 4. This movement will be continued until the collar 35 strikes against spring 24 and moves it away from contact 25, which is a position corresponding to the position of the transmitting-pen while the paper is being shifted.

In Fig. 5 I have shown a modification in which the movements of the armature are caused directly by the closing of the circuits through coils e e' , respectively, in the usual manner, but in which the springs 2 3 and contact-stops 5 4 act to open and close shunts passing through resistances r r' . Thus when the armature 30 rests against contact-point 31 the circuit is closed through wire f , con-

tact 5, spring 3, wire b, coil e', battery Z, and wire a. As the armature 1 is drawn up to the coil e' the connection between spring 3 and contact 5 is broken and the current shunted 5 through resistance r'. The circuit connections between resistance r, contact-point 4, and spring 2 are similar, so that after each movement of the armature 1 a resistance will be shunted into the circuit of the coil attracting it. The magnetism which holds the armature in this position will thus be reduced and the promptness of its movement under the pull of the other coil will be increased, as well as economy of battery effected.

15 It will be understood that while I have shown and described the magnet E as consisting of a single magnet provided with two coils the same result may be obtained by using two separate magnets.

20 What I claim is—

1. In a telautograph, the combination of two magnetic poles, a vibrating armature therefor, means whereby on each movement of the armature toward one of the poles, the 25 circuit is closed energizing the other pole, and means for deenergizing the first-named pole after the energization of the second pole, whereby the reverse movement of the armature is initiated by deenergization of the dominant pole, substantially as set forth.

2. In a telautograph, the combination of a receiving-pen, an escapement for controlling the movements of the same, a magnet for controlling the escapement, an armature for 35 said magnet and circuit connections for closing the circuits of both coils in each position of the armature and opening the circuit of one of the coils to cause the armature to move, substantially as set forth.

3. In a telautograph, the combination of a receiving-pen, an escapement for controlling the movements of the same, a magnet having two coils for controlling the escapement, a

vibrating armature vibrated by the coils of said magnet, circuit connections operated by 45 the armature such that as the armature moves toward each coil in succession, a circuit is closed through the second coil, by which latter circuit the magnetism which produces the next change of position of the armature is developed, means independent of said armature for maintaining the energization of the first coil after the energization of the second, and means for deenergizing the first coil to cause movement of the armature, substantially as 55 set forth.

4. The combination of magnets D and E, a circuit for each of the coils of magnet E controlled by the armature of magnet D, and a circuit for each of the coils of magnet E controlled by the armature of magnet E, the connections being such that the interruption of either of the circuits controlled by the armature of magnet D causes the armature of magnet E to move under the effect of the magnetism of one of the circuits controlled by the armature of magnet E, substantially as 65 set forth.

5. In a telautograph, the combination of a receiving-pen, an escapement for directly propelling the same, a magnet for controlling said escapement, a vibrating armature for said magnet provided with circuit makers and breakers, whereby the movement of the armature is continued automatically, and means 70 connected with the receiving-pen for opening the circuits of the escapement-magnet when the receiving-pen comes to a position of union, substantially as set forth.

In testimony whereof I have hereunto set 80 my hand in the presence of two subscribing witnesses,

GEORGE S. TIFFANY.
